MEDICATION CONTAINER

Alfred Barol, Philadelphia, Pa., assignor to John Wyeth & Brother, Incorporated, Philadelphia, Pa., a corporation of Delaware

Application March 28, 1941, Serial No. 385,767

10 Claims. (Cl. 206—46)

This invention relates to medication containers and more particularly to a container of such character essentially adapted to contain pre-weighed units of soluble medication for dosage other than oral, the container being so designed to provide compact and convenient packaging and to clearly indicate that the contained medicament is not for oral dosage.

Certain soluble medications, such as silver salts, are used in the treatment of diseases of the ear, 10 nose, throat, vagina, urethra, etc., and must be pre-weighed in order to provide proper strength of solution before application. At the same time these medications are not suitable for oral administration and any package therefor must 15 clearly indicate the non-suitability of its contents for oral use.

This invention contemplates, therefore, a package containing accurately pre-weighed amounts of a medication, safe for transport, convenient of 20 use and of an appearance and construction clearly indicating that it is not intended for oral use.

Referring to the accompanying drawing forming a portion of this specification and wherein 25 similar reference numerals indicate the same parts throughout.

Fig. 1 is a side elevation of the container.

Fig. 2 is a perspective showing the label in position to disclose directions for use.

Fig. 3 is an enlarged horizontal section through the device.

Fig. 4 is a section on line 4—4 of Fig. 1.

Fig. 5 is a perspective of a unit ready for use, and

Fig. 6 is a view showing the method of use.

6 indicates the body portion comprising an open ended tube formed of glass or suitable plastic to which is secured, by a narrow strip of adhesive, a label 7 bearing on its outer surface contents indications 8 and on its inner surface directional data 9. The label 7 is rolled about the tube 6 for shipment and is unrolled, as in Fig. 2, to disclose the directions for use, said label adhering to the tube 6, as shown. Stoppers or closures 10—10, one for each end of the tube 6 are provided and are formed of rubber or other suitable material. Each of these closures consists of a portion 11 adapted to enter the tube 6 and having a series of longitudinal projecting ribs 12 and a portion 13 of larger diameter than the part 11 and forming therewith an abutment 14 engaging the end of the tube 6 to completely close the same. Ribs 15 are provided on the portion 13 to

form finger grips to facilitate removal of the closures 10 from the tube 6.

Each of the closures 10 has an internal cavity 16 with a concave bottom 17 to form a seat for the usual form of two part capsule which comprises a longer portion 18 and a shorter portion 19. This internal cavity 16 is of such shape and size as to effectively grip and retain the shorter or "closure" portion of the two piece capsule, so that when the rubber member 10 is lifted away from the filled part of capsule, it always carries with it and removes the "closure" or shorter part of capsule, exposing the filled member ready for use in preparation of solution, and obviously unsuited for administration by mouth. At this point, it should be explained that the usual form of capsule and the filling machines therefor, present the most satisfactory and accurate method of pre-weighing and packaging the soluble medication which must be of certain strength in final solution. Such encapsulation, however, presents no indication that the filled capsule is not proper for oral use.

The filled capsule, containing an exact pre-weighed amount of medication is inserted in the cavity 16 and tightly fits therein until it seats in the concave bottom 17 thereof, the shorter part 18 of the capsule being innermost in the assembly. Closures 10 are now pushed inwardly into tube 6 until the abutment 14 rests against the end of the tube. Ribs 12 contact the inner surface of tube 6 and, being of such a height as to form a drive fit with the tube interior, are slightly compressed during the stoppering operation and transmit such compression, due to the elastic construction of the closure, to the walls of cavity 16 to prevent dislodgement of the seated capsule during shipment. To further avoid spilling of the capsule contents should accidental separation of the parts 18 and 19 occur, the tube 6 is made of such length that the space 20 between the two capsules in assembled relation, is such that the longer portion 18, if dislodged, will contact the opposite capsule and remain in alignment with the embedded portion 19, preventing any spilling.

When it is desired to use one of the pre-weighed units to form a solution, the unit is removed from the tube 6 by means of the portion 13 and is then in the form shown in Fig. 5. With the capsule embedded in the rubber holder immediate indication is given that the capsule is not for oral dosage. To use the contained medication the longer portion 18 of the capsule is removed containing the soluble material which can

then be added to the proper amount of liquid in container 21, as seen in Fig. 6. The short portion 19 of the capsule remains embedded in the cavity 16 of closure 10.

There is thus provided a medicament container carrying pre-weighed units of medication so assembled as to insure accuracy of amount, safety as to proper use and convenience in solution preparation.

What I claim is:

1. A container comprising a tube, a closure having a cavity extending inwardly from one of its ends, a hollow capsule comprising capsule sections one of which capsule sections is seated in said cavity and another of which capsule sections is removable therefrom while so seated, said closure being insertable with said end foremost into the tube and including a portion surrounding the said one capsule section, and said portion being of a diameter and material to clamp said one capsule section and closure together through insertion of said portion into and disposition within the tube.

2. A container comprising a tube, a closure having a cavity extending inwardly from one of its ends, a hollow capsule comprising capsule sections one of which capsule sections is seated in said cavity, and forms a lining for said cavity and another of such capsule sections projects beyond said one end and removably fits within the said one capsule section, said closure being insertable with said end foremost into the tube and including a portion surrounding the said one capsule section, and said portion being of a diameter and material to clamp said one capsule section and closure together through insertion of said portion into and disposition within the tube.

3. A container comprising a tube, a closure having a cavity extending inwardly from one of its ends, a hollow capsule comprising capsule sections one of which capsule sections is seated in said cavity and another of which capsule sections is removable therefrom while so seated, said closure being insertable with said end foremost into the tube and including a portion surrounding the said one capsule section, external ribs on said portion, said portion being elastic, and said portion being of a diameter through the ribs to cause compression of said portion about said one capsule section to clamp the latter and closure together through insertion of said portion into and disposition within the tube.

4. A container comprising a tube, a closure having a cavity extending inwardly from one of its ends, a hollow capsule comprising capsule sections one of which capsule sections is seated in said cavity and another of which capsule sections is removable therefrom while so seated, said closure being insertable with said end foremost into the tube and including a portion surrounding the said one capsule section, said portion being elastic and of a diameter to cause compression of the same about said one capsule section to clamp the same and closure together through insertion of said portion into and disposition within the tube, said one capsule section constituting a lining for said cavity and the other capsule section projecting beyond the same and said one end, and the closure having a portion of larger diameter than the first mentioned portion providing a shoulder at the junction of the portions adapted to abut one end of the tube.

5. A container comprising a tube, closure means in the opposite ends thereof, each of said closure means being removable, a hollow capsule located

within the tube carried by the removable closure means including a removable capsule section, the distance from said section to the other closure means being less than the distance necessary to move said section to separate same from its closure means whereby movement of the section will be limited by abutment with the opposite closure means to avoid danger of accidental discharge of the contents of the capsule into the tube.

10. 6. A container comprising a tube, removable closures in the opposite ends thereof, hollow capsules located within the tube carried one by each removable closure including a removable capsule section, the distance between said sections being less than the distance necessary to move either section to separate the same from its closure whereby movement of each section will be limited by abutment with the other section to avoid danger of external discharge of the contents of either capsule into the tube.

7. A closure of the class described comprising a body having a cavity extending inwardly from one end thereof, a hollow capsule having a section seated in said cavity and a capsule section engaged with the first mentioned section for removal from the closure independently of the first section, and said body having means disposed about said first section for insertion into a container and through engagement with the wall of such container to clamp said means against the said first section.

8. A closure of the class described comprising a body having a cavity extending inwardly from one end thereof, a hollow capsule having a section seated in and lining said cavity, and a capsule section engaged with the first mentioned section and extending beyond the same and body at said end for removal independently of the first section, and said body having an elastic portion disposed about said first section for insertion into a container and through engagement with the wall of the latter to clamp said portion against the first section.

9. A closure of the class described comprising an elastic body having a cavity extending inwardly from one end thereof, a hollow capsule having a section seated in said cavity and a capsule section engaged with the first mentioned section for removal from the closure independently of the first section, said body having a portion disposed about said first section, said portion having external ribs and being insertable into a container and through engagement with the walls of the container adapted to clamp said portion at said ribs against the first section of the capsule.

10. A closure of the class described comprising an elastic body having a cavity extending inwardly from one end thereof, a hollow capsule having a section seated in said cavity and a capsule section engaged with the first mentioned section for removal from the closure independently of the first section, said body having a portion disposed about said first section, said portion having external ribs and being insertable into a container and through engagement with the walls of the container adapted to clamp said portion at said ribs against the first section of the capsule, said removable capsule section extending beyond the first section and the body at said end, and the closure having a portion of larger diameter than the first mentioned portion providing a shoulder at the junction of the portions adapted to abut one end of the tube.

ALFRED BAROL.
